DESIGN FOR A COMBINATION RECEPTACLE FOR BEER SCRAPERS OR THE LIKE AND SUPPORT

Clifford A. McBride, East Providence, R. I.

Application February 13, 1939, Serial No. 82,969

Term of patent 14 years

To all whom it may concern:

Be it known that I, Clifford A. McBride, a citizen of the United States of America, residing at East Providence, in the county of Providence and State of Rhode Island, have invented a new, original, and ornamental Design for a Combination Receptacle for Beer Scrapers or the like and Support, reference being had to the accompanying drawing, forming part thereof.

Fig. 1 is a front elevational view of a combination receptacle for beer scrapers or the like and support embodying my new design.

Fig. 2 is a side elevational view thereof.

Fig. 3 is a top plan view thereof.

The essential feature of my design resides in the combination of the relatively large receptacle angularly supported within a counter-like base substantially as shown.

I claim:

The ornamental design for a combination receptacle for beer scrapers or the like and support, substantially as shown and described.

CLIFFORD A. McBRIDE.
